CLAIM

The ornamental design of an exhaust header, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an exhaust header incorporating the design; and,

FIG. 2 is another perspective view thereof.

The areas de-emphasized as faded out and bound by dashed lines illustrate portions of the exhaust header and environment that form no part of the claimed design.
